UNITED STATES PATENT OFFICE.

LEON P. LOWE, OF SAN FRANCISCO, CALIFORNIA.

APPARATUS FOR MAKING GAS.

No. 833,070.

Specification of Letters Patent

Patented Oct. 9, 1906.

Application filed August 9, 1905, Serial No. 273,368.

To all whom it may concern:

Be it known that I, LEON P. LOWE, a citizen of the United States, residing at San Francisco, in the county of San Francisco and State of California, have invented certain new and useful Improvements in Apparatus for Making Gas, of which the following is a specification.

This invention relates to an apparatus for manufacturing gas, the object of the invention being to provide an apparatus which can be used to manufacture gas with greater economy than heretofore.

In the accompanying drawings, Figure 1 is a side elevation of the apparatus, the generator being shown in vertical section. Fig. 2 is a plan view thereof.

Referring to the drawings, 1 represents the casing of a generating-chamber, the main portion of which is divided by arches 2 into three compartments 3 4 5, each compartment supporting refractory material 6. The uppermost compartment 5 connects with a flue 7, closed by a valve 8 and leading to the mouth of a stack 9. The lowest compartment 3 connects with a passage 10, formed by a partition 11 and a protective wall 12, the latter forming the back of a coking and combustion chamber 13, said passage connecting with said chamber over the top of said wall. The coking-chamber 13 is provided with an upper door 27 for admitting the material to be coked and with a lower door 28 for removing the coke. Into the top of said coking and combustion chamber 13 discharges an oil-pipe 14, the oil being atomized by steam through a pipe 15. Air for combustion is also supplied by a pipe 16, controlled by a valve 17. Into the top of the uppermost compartment 5 discharges a steam-pipe 18, and into the top of the intermediate compartment 4 discharges an oil-pipe 19, the oil being atomized by steam through a pipe 20. From the top of the lowest compartment 3 leads a gas-outlet pipe 21, which also connects with the top of the coking and combustion chamber 13 by a branch 22, controlled by a valve 23, which may be used to close either the pipe 21 or the branch 22. The pipe 21 leads to a washer 24, from which the gas passes by a seal 25 to the usual scrubbers, purifiers, &c.

The operation of the apparatus is as follows: The material to be coked having been charged into the coking-chamber, the first step of the process is the heating stage, in which

oil at the burner 14 is burned by means of air admitted through the pipe 16. This combustion is continued a considerable time, the products of combustion impinging against the protective wall 12, passing down the passage 10, and then up through the several chambers 3 4 5 in succession, heating the refractory material 6 therein and escaping by the flue 7. The refractory material having been sufficiently heated for the purpose of gas-making, the valves 8 and 17 are closed, and the gas-making stage commences.

In order to understand the nature of this invention, it is to be remembered that when oil is passed over sufficiently highly heated refractory material it is broken down and converted into solid carbon in the form of lamp-black and into gaseous products of varying luminosity, the degree of luminosity of the gases so produced varying with the heat applied thereto. If the heat be sufficiently great, the resulting gases may be principally non-luminous gases, such as hydrogen and marsh gas. As the temperature of the refractory material falls the oil is not so highly decomposed; but gases of greater chemical complexity and greater luminosity are produced—that is to say, in the process of gas-making by which oil is partly broken down into solid carbonaceous substances the first, gases which are produced when the gas-making stage commences are of very low candle-power, which increases as the gas-making stage progresses. All of these gases are, however, commingled in the gas-holder, so that a substantially uniform gas results. However, by my present apparatus the gas produced is substantially uniform as it is produced. The principal advantage of this is that the gas is produced more economically and with less waste of oil converted into solid carbon than with such heretofore existing processes. Therefore after the preliminary stage of heating has been carried on to a sufficient extent the air-blast is shut off by the valve 17 and the valve 8, leading to stack 9, is closed. Steam is introduced through the pipe 18, and oil is introduced through the pipes 19 and 14, atomized, respectively, by the steam-pipes 20 and 15. The steam introduced through the pipe 18 is superheated by the refractory material in chamber 5 and mixes with the oil introduced through the pipe 19, combining with that portion of the oil broken down into solid carbon to form hydrogen and carbonic-oxid gases, a portion of the oil forming

2 a rich fixed oil-gas. At the same time the oil passed through the pipe 14, together with a certain amount of steam admitted through pipe 15, and the gases distilled from the tarry residue are passed upward through the highly-heated chamber 3, the effect being to break down the oil largely into solid carbonaceous form and non-luminous gases. These gases intermingle in the top of the chamber 3 with the fixed gases of comparatively high candle-power obtained from the steam and oil passing downward, and the resulting gas is drawn off by the pipe 21, being a gas of substantially the required degree of luminosity. As the temperature of the refractory material in chamber 3 falls less solid carbon is formed and the candle-power of the gas increases, and the amount of oil passed through the pipe 19 may be gradually diminished in order to prevent too rich a gas being formed. By this means the luminosity of the gas produced is maintained substantially uniform. By means of the valve 23 the apparatus may be used, if desired, in the ordinary manner of making gas—that is, by raising the valve 23 so as to close the pipe 21 to the generator all the gas may be caused to pass downward through the refractory material in the compartments 5 4 3 and through the branch pipe 22 at the top of the coking and combustion chamber.

I claim—

1. An apparatus for making gas comprising a casing forming a chamber, a wall segregating a portion of the chamber from the main portion to form a coking and combustion chamber, refractory material in the main portion, an outlet-pipe leading from an intermediate point of the main portion, means for admitting steam and oil at points on the opposite side of the outlet from the coking-

chamber, and means for introducing oil into said coking-chamber, substantially as described.

2. An apparatus for making gas comprising a casing forming a chamber, refractory material in said chamber, a wall within said casing forming with the wall of one of the compartments a passage, and with the casing a coking and combustion chamber, means for admitting atomized oil into said coking and combustion chamber, an outlet for conducting the gases from an intermediate point of the casing, and means for admitting atomized oil and steam into the chamber on the side of the outlet opposite to said coking-chamber, substantially as described. 45 50 55

3. An apparatus for making gas comprising a casing, refractory material within said casing, an outlet-pipe leading from an intermediate point of the casing, means for burning oil at one end of the casing, means whereby the products of combustion may be passed in one direction entirely through said casing, whereby the refractory material next to the point of combustion of said oil is more highly heated than the remaining refractory material, means for excluding air and for passing oil and steam through a portion of the refractory material on the side of the outlet nearest the point of combustion in one direction, and means for simultaneously passing oil and steam in the other direction through a portion of the refractory material on the other side of the outlet, substantially as described. 60 65 70 75 75

In witness whereof I have hereunto set my hand in the presence of two subscribing witnesses.

L. P. LOWE.
